UNITED STATES PATENT OFFICE

HOWARD R. FONDA, OF ST. ALBANS, VERMONT

TOY

Application filed July 5, 1929. Serial No. 376,158.

This invention relates to a novelty device which is designed and adapted to be positioned on vehicles, such as automobiles, bicycles and the like, said device being in the 5 form of a figure, together with means operable by the pressure of air, to put the figure in motion.

The principal object of the invention is the provision of a device of the indicated character embodying novel features of construction and operation hereinafter fully described and illustrated in the accompanying drawing, in which—

Figure 1 is a sectional elevation of a 15 device embodying the features of the invention.

Fig. 2 is a sectional view taken on the line 2—2 of Fig. 1.

Fig. 3 is a front elevation of the propeller 20 of the device, the blades thereof being shown extended.

Fig. 4 is a view illustrating the blades of the propeller folded or collapsed.

Fig. 5 is a view of the intermediate propeller blade.

Fig. 6 is a detail section taken on the line 6—6 of Fig. 4.

Referring now more particularly to the several views of the drawing, it will be apparent that the device includes a Figure 10 which may be of any preferred form in simulation of some natural or unnatural object. In the present instance the figure is in the form of a man including a body 11 having 35 jointed arms 12 and jointed legs 13. A tubular member 14 extends downwardly from the body 11, and has a plate or disk 15 on the lower end thereof. The device also includes attaching means which may be of any preferred form, and in the present instance, is 40 in the form of a clamp, consisting of cooperating members 16 and 17, and screws 18 which serve to hold the members 16 and 17 in clamping engagement with a suitable support 19. 45 The support 19 may constitute an appurtenance of a vehicle such as an automobile or bicycle on which the device is to be mounted. A post or rod 20 is secured as at 21 to the member 16 of the clamp. The tubular member 14 on the body 11 of the figure receives

the post or rod 20 therein, so that said figure may be moved up and down on the post or rod 20. A bracket 22 is provided, and in the present instance is formed as a continuation of the post or rod 20, the material being bent to provide coils 23 and a horizontally disposed member 24 which constitutes a stop. The coils 23 receive therein and have secured thereto a tubular member 25 which serves as a bearing for a shaft 26 having a crank 27 at one end. The crank 27 cooperates with the disk 15 on the lower end of the tubular member 14, to cause the up and down movement of the figure 10 upon the rotation of the shaft 26.

Motion is imparted to the shaft 26 by a wind propeller consisting of blades 28, 29 and 30. The blade 28 is weighted as at 31 on the outer end, and the inner end thereof has a hub 32. Each of the blades 28 and 30 has an arcuate slot 33, and the intermediate blade 29 has a hole 34 in the inner end located so as to register with the slots 33. The blades 29 and 30 are held against axial movement on the hub 32 by a collar 35 and a set screw 36 carried by the collar. The screw 36 is received in a tapped hole in the hub 32. The said screw 36 also engages the shaft 26 in order to cause rotation of the shaft with the propeller. The propeller blades are held in the extended relationship as shown in Fig. 3 by a screw 37 and clamp 38 in threading engagement with the screw 37. The screw 37 extends through the slots 33 in the blades 28 and 30 and the hole 34 in the blade 29.

From the foregoing it will be understood that when the device is mounted on a vehicle, and such vehicle is in motion, pressure of air on the propeller will cause it to rotate, and through the intervention of the hub 32, shaft 26, crank 27, disk 15 and member 14, the figure 10 will be caused to move up and down on the post or rod 20. It will also be apparent that by collapsing the propeller blades, as shown in Fig. 4, the figure 10 may remain at rest. The propeller blades are collapsed by loosening the nut 38 on the screw 37, enabling the blades to be brought side by side after which the nut 38 may be tightened to hold the blades in this relationship. The shaft 26

may be adjusted with respect to the hub 32 by loosening the screw 36, to bring the crank 27 in the up position while the blades are in the depending position, after which the screw 36 may be tightened to maintain this relationship. The propeller blades will then balance the figure 10. It will also be apparent that the disk 15 will engage the stop 24 to prevent separation of the figure from the post or rod 20.

10 I claim:

1. A device having the combination of a figure, a post having means for attaching it to a suitable support, means connected with the figure and having axial movement on said post in opposite directions, and air pressure operated means comprising a propeller, a crank connected with and operated by the propeller, and a disk connected with the figure and operated by the crank, to cause the axial movement of said figure.
- 15 2. A device having the combination of a figure, a post having means for attaching it to a suitable support, means connected with the figure and having up and down movement on said post, means limiting the up and down movement of said figure, and air pressure operated means comprising a propeller, a crank connected with and operated by the propeller, and a disk connected with the figure and operated by the crank, to cause the up and down movement of said figure.

HOWARD R. FONDA.
